UNITED STATES PATENT OFFICE.

WILLIAM B. JARVIS, OF GRAND RAPIDS, MICHIGAN.

RADIATOR CAP.

Application filed July 30, 1926. Serial No. 125,919.

The main objects of this invention are: First, to provide an improved radiator cap which is well adapted to carry or serve as a support for ornaments which is effectively sealed against the escape of water or steam and also one in which the ornamental parts are properly aligned or positioned relative to the radiator.

Second, to provide a cap having these advantages which is simple and economical in structure and not likely to become inoperative for the purpose intended as a result of severe usage.

Objects pertaining to details and economies of the invention will definitely appear from the detailed description to follow. The invention is clearly defined and pointed out in the claims.

A structure embodying the features of the invention is clearly illustrated in the accompanying drawing forming a part of this application, in which:

Fig. 1 is a vertical section of a structure embodying the features of my invention, the ornamental projecting parts being partially broken away and the shank of a supported ornament, motometer or the like being indicated by dotted lines.

Fig. 2 is a top perspective view.

Fig. 3 is a perspective view of the internal parts in disassembled relation.

Referring to the drawing, 1 represents the threaded neck of an automobile radiator. In the embodiment illustrated the cap 2 is internally chambered and provided with internal threads to engage the neck.

The cap illustrated is provided with ornamental projections partially shown at 3, the shank of a top ornament or the like being indicated by dotted lines at 4. These, however, form no part of my invention but are illustrated in order to bring out some of the advantages of the structure.

The cap has a central bore 5 through the top to receive the shank of a supported part, this bore being closed when the cap is finished without any top ornament and adapted to receive such by means of a closure disk 6 which may be punched out to receive the stem of the ornament or supported part.

Depending within the cap is an annular flange-like support 7 having an internal shoulder 8 engaged by the lip or flange 9 on the closure plate 10. This closure plate has a bore corresponding to that of the cap and

registers therewith, the lip being in the form of a flange around the hole in the plate.

The cap also has a downwardly facing annular groove 11 which is adapted to receive the blade or tongue-like springs 12 struck up from the annular thrust member 13, these tongues being arranged in the groove 11 to position the thrust member laterally and also prevent such collapsing of the springs as would destroy their usefulness or set them. The dimensions of the thrust member are such that it engages the cap at the edge of the groove.

A resilient gasket 14 is arranged between the closure plate and the end of the neck 70 of the radiator as shown in Fig. 1. This combination of thrust member, closure plate and gasket yieldingly supports the gasket so as to prevent injury to the same as the cap is screwed down and also serving as a friction means for holding the cap in its adjusted positions with its projecting parts properly located relative to the radiator. Further, a seal is provided so that water or steam does not pass above the gasket and 80 down at the outside thereof between the threads. A very perfect seal is provided, and as stated the gasket is protected so that it is not distorted or injured by the cap being screwed down too far.

I have illustrated and described an embodiment of my improvements which I have found very satisfactory. I have not attempted to illustrate or describe other embodiments or adaptations which I contemplate as I believe this disclosure will enable those skilled in the art to embody or adapt my improvements as desired.

Having thus described my invention what I claim as new and desire to secure by Letters Patent is:

1. The combination with a threaded neck, of a chambered cap having a central bore in the top thereof with a downwardly projecting internally shouldered flange at its lower end, said cap having an internal annular groove therein, a gasket arranged to engage the end of the neck, an annular thrust member for applying yielding pressure to said gasket and for retaining the cap in adjusted positions on said neck, said thrust member having a plurality of spring members struck up therefrom, the outer ends of said spring members being disposed in said annular groove, the thrust member being of 110

such size as to engage the cap at the side of the groove when the springs are fully compressed, and a closure member disposed with its outer edge between said thrust member and gasket and provided with a bore registering with the bore of said cap and with an upturned flange-like lip about its bore engaged in the recess formed by the shoulder in said cap flange.

- 10 2. The combination with a threaded neck, of a chambered cap having a central bore in the top thereof with a downwardly projecting flange at its lower end, said cap having an internal annular groove therein, a gasket 15 arranged to engage the end of the neck, an annular thrust member for applying yielding pressure to said gasket and for retaining the cap in adjusted positions on said neck, said thrust member having a plurality of 20 blade spring members disposed in said annular groove, and a closure member disposed with its outer edge between said thrust member and gasket and engaged with said cap flange.
- 25 3. The combination with a threaded neck, of a chambered internally threaded cap having an internal downwardly projecting support member and an internal annular groove in the top, a thrust member provided with 30 springs engaged in said groove, a gasket disposed to engage the end of the neck, and a closure plate mounted on said support with its outer edge disposed between said gasket and said thrust member.
- 35 4. The combination with a threaded neck, of a chambered internally threaded cap having an internal downwardly projecting support member, a spring thrust member, a gasket disposed to engage the end of the neck, and a closure plate mounted on said support with its outer edge disposed between said gasket and said thrust member.
- 40 5. The combination with a threaded neck,

of a chambered cap having a depending support, a closure plate engaging with said support whereby it is held in a central position, a thrust member disposed above said closure plate, and a gasket disposed between said closure plate and the end of the neck, said thrust member constituting means for applying yielding pressure to the gasket and retaining the cap in its adjusted positions on the neck.

6. The combination with a threaded neck, of a chambered internally threaded cap having an internal annular groove in the top, an annular thrust member provided with integral springs engaged in said groove, and a gasket disposed below urged against said thrust member.

7. The combination with a threaded neck, of a chambered internally threaded cap having an internal annular groove in the top thereof, a thrust member provided with a plurality of integral springs disposed with their outer ends in said groove, and a gasket disposed to engage the end of the neck, said thrust member constituting means for applying yielding pressure to the gasket and retaining the cap in its adjusted position on the neck.

8. The combination with a threaded neck, of a chambered cap having a downwardly facing internal groove and a downwardly projecting internal closure plate support member, a closure plate, a gasket arranged between the end of the neck and said closure plate, and an annular thrust member acting on said closure plate for applying yielding pressure to said gasket and retaining the cap in adjusted positions on said neck, said thrust member having a plurality of spring members engaged in said groove.

In witness whereof I have hereunto set my hand.

WILLIAM B. JARVIS.
